US00D963632S

(12) **United States Design Patent** (10) **Patent No.:** **US D963,632 S**
Lee et al. (45) **Date of Patent:** **** Sep. 13, 2022**

(54) **MOBILE PHONE**

(71) Applicant: **LG ELECTRONICS INC.**, Seoul (KR)

(72) Inventors: **Jonghak Lee**, Seoul (KR); **Sojin Kim**, Seoul (KR); **Jinki Min**, Seoul (KR); **Hongkyu Park**, Seoul (KR); **Seunghyun Ji**, Seoul (KR)

(73) Assignee: **LG ELECTRONICS INC.**, Seoul (KR)

(**) Term: **15 Years**

(21) Appl. No.: **29/708,894**

(22) Filed: **Oct. 10, 2019**

(30) **Foreign Application Priority Data**

Apr. 10, 2019 (JP) 2019-007912

(51) **LOC (13) Cl.** **14-03**

(52) **U.S. Cl.**

USPC **D14/248**

(58) **Field of Classification Search**

USPC ..... D14/138 AD, 138 R, 138 AA, 341, 345, D14/346, 203.1, 203.3, 203.4, 203.7, 248, D14/138 G, 132, 501, 336, 496; D21/517; D6/704; D16/241 CPC H04M 1/0237; H04M 1/206; H04M 1/208; H04M 1/0241; H04M 1/0268; G06F 1/1652; G06F 1/1624

(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof; and,

FIG. 9 is a rear perspective view showing the use state in which rear display part is operated, showing example displayed information.

The broken lines depict portions of the mobile phone, and example displayed information in FIG. 9, that form no part of the claimed design. The dash-dot broken lines define the bounds of the claimed design and form no part thereof.

1 Claim, 9 Drawing Sheets
